Thomas A. Siegel

UNITED STATES PATENT OFFICE.

CASPER KUHN, OF CARLSTADT, NEW JERSEY.

WINDOW-GUARD.

1,257,887.

Specification of Letters Patent. Patented Feb. 26, 1918.

Application filed January 13, 1916. Serial No. 71,905.

To all whom it may concern:

Be it known that I, CASPER KUHN, a citizen of the United States, residing at Carlstadt, in the county of Bergen and State of New Jersey, have invented certain new and useful Improvements in Window-Guards, of which the following is a specification, reference being had therein to the accompanying drawing.

10 My invention relates to improvements in window guards or safety appliances, and more particularly has reference to a device or attachment adapted for use in an open window such as the window of a home 15 where children are apt to climb out or where a person is apt to fall through in hanging clothes, and has for its object to provide a simple form of device adapted to be fitted and removed conveniently to prevent such 20 accident.

Referring to the accompanying drawings, Figure 1 illustrates in perspective the window casing and frame showing an application of my invention, and Fig. 2 a cross section on the line 5—5 of Fig. 1.

It will be seen that within the guideway 6 of the window frame 7 may be introduced uprights such as 8, one in each side. These uprights are provided with bars or tubes 30 such as 9—10, the bar 9 being adapted to slide within the tube 10 so that the same may be introduced into the window and spread out into the guideways 6 thereof. The bar 9 is also preferably provided with

a cut away portion or recess into which a 35 ring such as 11 may be seated, said ring being adjacent the end of the tube 10 as shown and of sufficient diameter to receive the shackle of the padlock 12 to retain said ring within said cut-away portion. From which 40 it will be seen that after the guard has been placed in position it may be securely locked to prevent being shifted. When it is desired to take the guard out of the window, the lock is merely removed from the ring 11 45 which allows the ring to slide leftwardly over the bar 9 and allows the bar 9 to be telescoped into the tube 10 so that the guard may be readily withdrawn.

I claim—

In a window guard, a pair of uprights adapted to fit within the casing of a window, one of said uprights having rods extending laterally therefrom, the other of said uprights having tubes extending laterally therefrom and over the free ends of said rods, a recess in one of said rods, a ring seated therein, and the shackle of a padlock within and filling the free portion of said ring to prevent the escape of same 55 from said recess, whereby said guard may be retained within said window casing.

In testimony whereof I hereunto affix my signature in the presence of two witnesses.

CASPER KUHN.

Witnesses:

LOUISE ENDERLE,
THOMAS A. HILL.
